DESIGN FOR A DRINKING CUP DISPENSER AND DISPOSER UNIT

Howard B. Hait, Philadelphia, Pa.

Application November 17, 1943, Serial No. 111,708

Term of patent 7 years

(Cl. D67—4)

To all whom it may concern:

Be it known that I, Howard B. Hait, a citizen of the United States, residing at Philadelphia, in the county of Philadelphia and State of Pennsylvania, have invented a certain new, original, and ornamental Design for Drinking Cup Dispenser and Disposer Unit, of which the following is a specification, reference being had to the accompanying drawing, forming part thereof.

In the drawing:

Fig. 1 is a front elevational view of a drinking cup dispenser and disposer unit showing my new design.

Fig. 2 is a side elevational view of the same.

Fig. 3 is a top view of the unit.

As Fig. 1 is viewed, on the left side of the unit is a receptacle for cups. In the center is a receptacle for water. To the right of the receptacle is a disposer for holding used cups. The unit is adapted to be mounted adjacent to the water faucet of a water cooler.

I claim:

The ornamental design for a drinking cup dispenser and disposer unit, substantially as shown and described.

HOWARD B. HAIT.
